UNITED STATES PATENT OFFICE

HENRY W. HILDEBRAND, JR., OF DENVER, COLORADO, ASSIGNOR TO INLAND PAPER
BOX COMPANY, OF DENVER, COLORADO, A CORPORATION OF COLORADO

NONSIFTING, ONE-PIECE, POWDER BOX DRUM

Application filed June 19, 1931. Serial No. 545,437.

This invention relates to a drum for cardboard, face powder boxes and has for its principal object the provision of a drum for this use which will be formed of a single piece 5 of cardboard and which will be an absolute protection against sifting or leakage.

Another object of this invention is to so construct the drum that the entire top thereof can be easily broken away, if desired, to 10 obtain access to the full face of the powder.

Other objects and advantages reside in the detail construction of the invention, which is designed for simplicity, economy, and efficiency. These will become more apparent 15 from the following description.

In the following detailed description of the invention reference is had to the accompanying drawing which forms a part hereof. Like numerals refer to like parts in all views 20 of the drawing and throughout the description.

In the drawing:

Fig. 1 is a plan view of the one piece blank employed in the improved drum.

25 Fig. 2 illustrates the blank partially folded.

Fig. 3 illustrates the completed drum.

Fig. 4 is a bottom view of the completed drum.

Fig. 5 illustrates the drum in place in a 30 powder box.

Fig. 6 illustrates the drum opened to allow access to the powder.

The invention comprises a blank, such as 35 illustrated in Fig. 1, cut from card or box-board. The blank is provided with a bottom 10 having a filling opening 11 and a top 12 cut out, as shown at 13, to allow access to the powder.

The bottom 10 and top 12 are each provided 40 with side flaps 14 arranged to fold along the fold lines 15 to form the sides of the drum. One of the flaps 14 acts to connect the top to the bottom as shown in Fig. 1. The top 12 is perforated along diagonal lines as shown 45 at 16. The perforated lines 16 extend from the corner of the cutout 13 to the corners of the fold lines 15.

The drum is assembled by folding the flaps 14 upwardly on the top and bottom portions 50 10 and 12 and then folding the series of side

flaps 14 which surround the bottom 10 into the series of side flaps 14 which surround the top 12 as shown in Fig. 2. Thus forming a complete hollow drum with double side walls.

An ornamental paper binding 17 is now 55 glued or pasted over the entire top and sides of the drum and is turned under and cemented around the bottom 10 as shown in Fig. 4. This forms an absolutely tight, sift proof drum with only one opening, that is, the bottom filling opening 11.

The drum is now filled with powder through the opening 11 and a powder box proper 18 is forced over the bottom so as to close the filling opening 11. The completed 65 box has the appearance illustrated in Fig. 5 with the drum forming a flange for the reception of the usual box lid.

When it is desired to use the powder, the paper covering 17 over the cut-out 13 is torn 70 or broken away, as shown in Fig. 6. Should a larger opening be desired so as to allow a powder puff to be used on the powder the sides of the cut-out 13 may be lifted so as to break them along the diagonal perforations 75 16 and along the fold lines 15 so as to expose the entire top of the powder.

The diagonal perforations 16 also serve another purpose in addition to allowing access to the powder. The usual powder box is 80 useless after the powder has been used. In the present case, however, the sides of the cut-out 13 can be easily broken from the box so as to allow the full interior of the drum to be used for other purposes after the powder 85 has been used.

While the invention has been described as particularly applicable to face powder boxes, it is, of course, not limited to this use but will be found valuable wherever it is desired 90 to completely protect the contents of a box and yet allow ready access thereto.

While a specific form of the improvement has been described and illustrated herein, it is desired to be understood that the same 95 may be varied, within the scope of the appended claim, without departing from the spirit of the invention.

Having thus described the invention, what 100

is claimed and desired secured by Letters Patent is:—

A drum for face powder boxes comprising: a one piece blank; a bottom portion on said blank; a top portion on said blank; a side portion connecting said top and bottom portions along one of their sides; side flaps formed on the other sides of both said top and bottom portions, the side flaps of the top and bottom portions overlapping so as to form a double wall around said drum; openings formed in both said top and bottom portions; a paper cover cemented over said drum so as to cover one of said openings and all of said side flaps; and a box portion arranged to fit snugly over said drum so as to cover the other opening.

In testimony whereof, I affix my signature.

HENRY W. HILDEBRAND, JR.
